CLAIM

The ornamental design for a portion of a round point shovel blade with teeth, as shown and described.

DESCRIPTION

FIG. 1 is a perspective view of a portion of a round point shovel blade with teeth according to our new design;

FIG. 2 is a top view thereof;

FIG. 3 is a bottom view;

FIG. 4 is a rear elevational view;

FIG. 5 is a front elevational view; and,

FIG. 6 is a side elevational view from the right in FIG. 5, the view from the opposite side being substantially a mirror image.

Broken line illustration in the drawing disclosure is not part of the design sought to be patented.
